(57) **CLAIM**

The ornamental design for an isothermal nucleic acid amplification meter, as shown and described.

DESCRIPTION

FIG. 1 is a perspective view from one side of an isothermal nucleic acid amplification meter;

FIG. 2 is a front elevation view of the isothermal nucleic acid amplification meter of FIG. 1;

FIG. 3 is a rear elevation view of the isothermal nucleic acid amplification meter of FIG. 1;

FIG. 4 is a right side elevation view of the isothermal nucleic acid amplification meter of FIG. 1;

FIG. 5 is a left side elevation view of the isothermal nucleic acid amplification meter of FIG. 1;

FIG. 6 is a top plan view of the isothermal nucleic acid amplification meter of FIG. 1; and,

FIG. 7 is a bottom plan view of the isothermal nucleic acid amplification meter of FIG. 1.

The broken lines in FIGS. 1-7 are included for the purpose of illustrating portions of the isothermal nucleic acid amplification meter and form no part of the claimed design.
